UNITED STATES PATENT OFFICE.

FRANCIS COLIN BRODIE, OF MOOSE JAW, SASKATCHEWAN, CANADA.

CIRCUIT-CONTROLLER FOR ELECTRIC SIGN

1,080,535.

Specification of Letters Patent.

Patented Dec. 9, 1913.

Application filed April 3, 1913. Serial No. 758,542.

To all whom it may concern:

Be it known that I, FRANCIS COLIN BRODIE, a subject of the King of Great Britain, and resident of Moose Jaw, in the Province of Saskatchewan, in the Dominion of Canada, have invented certain new and useful Improvements in Circuit-Controllers for Electric Signs, of which the following is the specification.

10 This invention relates to improvements in circuit controllers for electric signs, and the objects of the invention are to provide means by which a maximum amount of variation in the connection to the circuit 15 may be obtained, and further to enable the changes to be made with great rapidity whereby an aggregation of illuminating or other devices may be caused to display different figures or letters at the will of the 20 operator, and it consists essentially of the improved construction hereinafter described in detail in the accompanying specifications and drawings.

In the drawings, Figure 1 is an elevation, 25 partially diagrammatic, of an embodiment of the invention. Fig. 2 is a cross section through the controlling cylinder. Fig. 3 is a perspective view of one of the contact devices. Fig. 4 is a sectional detail through 30 one of the contact devices taken on the line 2-2, Fig. 3.

In the drawings like characters of reference indicate corresponding parts in all the figures.

35 Referring to the drawings, A represents a rotary controlling cylinder of insulating material, supported in any suitable way and adapted to be driven by suitable means which do not form part of the present invention. This cylinder carries on its surface longitudinal and peripheral rows of 40 contact devices B which are adapted to cooperate with pairs of contact fingers C carried on a fixed support D.

45 The pairs of contact fingers are arranged in a row on the fixed support and are placed to correspond with the peripheral rows of contact devices on the cylinder. For the sake of clearness only one row of contact 50 devices has been shown in Fig. 1 and three rows in Fig. 2. It will be understood, however, that the number of the contact devices may be adjusted to correspond with the nature of the work to be performed.

55 The pairs of contacts C each comprise separate contacts 10 and 11, each formed

with bifurcated spring ends 12 and 13 adapted to make firm contact with the contact devices. The members 10 and 11 are spaced a distance from each other and out of electric contact with each other, being themselves included in an electric circuit 14 which includes a source of power 15, said circuit including an illuminating device or lamp 16 which may form part of a sign 65 F, each pair of contacts thus controlling a similar lamp or illuminating device.

60 Each of the contact devices B comprises a socket member 17 formed with a base plate 18 and side plates 19 and 20 of spring metal, 70 which fit closely to an outwardly movable part 21 which is pivoted or hinged to the socket by means of a pin 22, being adapted to be retained in either extended or closed position by suitable means, such as projections 23 and 24 formed on the side plates adapted to fit into corresponding depressions or recesses formed on the plate or blade 21.

75 It will be seen that the plate or blade 21 80 may be turned outwardly at right angles to the surface of the cylinder or substantially tangential thereto and will be retained in either position.

80 It will be seen that by selecting the various lamps to be lighted and raising or lowering the corresponding blades on the contact devices the various letters, characters or pictures may be shown on the sign at the will of the operator as the cylinder revolves. 90

85 What I claim as my invention is:

1. A controller for electric circuits comprising in combination a plurality of pairs of fixed contact fingers, a rotary cylinder of insulating material, a plurality of contact devices thereon, each having an outwardly movable part adapted when extended to form a connection between the contact fingers of a determined pair when the cylinder is rotated. 95

100 2. A controller for electric circuits comprising in combination a plurality of pairs of fixed contact fingers, a rotary cylinder of insulating material, a plurality of contact devices thereon arranged in transverse and peripheral rows, each having an outwardly movable part adapted when extended to form a connection between the contact fingers of a determined pair when the cylinder is rotated. 105

110 3. A controller for electric circuits comprising in combination a plurality of pairs

of fixed contact fingers, a rotary cylinder of insulating material, a plurality of contact devices thereon, each having an outwardly movable pivoted blade adapted when extended to form a connection between the contact fingers of a determined pair when the cylinder is rotated.

4. A controller for electric circuits comprising in combination a plurality of pairs of fixed contact fingers, a separate electric circuit for each pair of fingers including an illuminating device and a source of power, a plurality of contact devices, each comprising a socket, a blade pivoted in the

socket, said socket having projections, and 15 said blade having corresponding recesses whereby the blade is held in raised or lowered position, said blade being adapted, when the cylinder is rotated, to complete the electric circuit between the contact 20 fingers of a given pair.

In witness whereof I have hereunto set my hand in the presence of two witnesses.

FRANCIS COLIN BRODIE.
